United States Patent

Des. 236,488
Patented Aug. 26, 1975

236,488

CALCULATOR CASE

Gregory F. Fossella, Marshfield, Mass., assignor to
Bowmar/Ali, Inc., Acton, Mass.

Filed Mar. 6, 1974, Ser. No. 448,478

Term of patent 14 years

Int. Cl. D18—01

U.S. Cl. D26—5 C

Fig. 1.

Fig. 2.

Fig. 3.

Fig. 4.

FIG. 1 is a front perspective view of a calculator case, shown with the cover closed, showing my new design;

FIG. 2 is a front perspective view thereof, shown with the cover in an open position;

FIG. 3 is a rear perspective view thereof, with the cover in the position shown in FIG. 2; and

FIG. 4 is a rear perspective view thereof, with the cover shown secured at the rear of the case.

I claim:

The ornamental design for a calculator case, as shown and described.
